UNITED STATES PATENT OFFICE.

JOHN J. ALISCS, OF NEW YORK, N. Y.

IMPROVEMENT IN BRIDGES.

Specification forming part of Letters Patent No. 44,498, dated October 4, 1864.

To all whom it may concern:

Be it known that I, JOHN J. ALISCS, of the city, county, and State of New York, have invented a new and Improved Swamp-Bridge; and I do hereby declare the following to be a full and exact description of the same, reference being had to the accompanying drawings, making part of this specification, in which—

Figure 1 is a side elevation of my improved swamp-bridge in use. Fig. 2 is a plan of a portion thereof. Figs. 3 and 4 are end views of the same.

Similar letters of reference indicate corresponding parts in the several figures.

This invention relates to a portable bridge, of simple and cheap construction, to be erected or set up in swamps and marshes so as to facilitate the passage of an army, army-wagons, &c., and permit the planting of batteries in places which have hitherto been considered unavailable and, in fact, inaccessible.

In order that others skilled in the art to which my invention appertains may be enabled to fully understand and use the same, I will proceed to describe its construction and operation.

In the accompanying drawings, A A represent piles or supports, two pairs of which with their appurtenances form one section of the bridge.

To obtain the requisite supporting area at top and adapt the bridge to remain in a steady and firm condition the piles A are crossed in pairs, as shown in Figs. 3 and 4, thus forming a trestle. They are connected at the center by a bolt, a, and these bolts are to be formed each with eyes a' a', in order that a connecting-rod may, if desired, be employed between the several sections of the bridge to impart longitudinal strength and rigidity thereto.

In the upper ends of the piles A are slots A', to receive bars or ties B of iron or other suitable material, one bar being employed in connection with each pair of piles, and serving as a coupling and brace at top, for which purpose the said bars and piles are fastened together by pins b.

In the piles A are a series of apertures, a'', each of which is adapted to receive the pins b and thus admit of the vertical adjustment

of the bars B for the purpose of bringing all the supporting-points at the same height and making the bridge level where the bottom of the swamp is uneven and undulating, as represented in Fig. 1.

The parts thus far described constitute the main supporting medium, and the piles are to be prevented from sinking when the bottom of the swamp is soft by having their lower ends inserted into broad flat sills C; but when the bottom is hard these boards may be dispensed with, and in lieu thereof are employed check-blocks C', shaped somewhat like a boot, one of these blocks being attached to the lower end of each pile A. The check-blocks C' will be all sufficient in most places where the bridge is brought into requisition, and while preventing the same from sinking or settling deeper than may be desired they impart lateral support and firmness to the bridge.

The drawings illustrate two methods of securing in position the sleepers and roadway D D', upon which the troops, wagons, &c., may pass over the swamp, or which may support a battery. In this latter use great advantage may be derived from the bridge, for the reason that the guns may be brought to bear upon the enemy from such position that the high grass and other swamp vegetation will completely conceal the gunners.

One method of securing the sleepers D consists in forming the bars B with strong flanges b' b', between which are inserted the ends of the sleepers D, the same being secured between the flanges by the pins b''. This method is clearly exhibited in Fig. 4. The other method is represented in Figs. 2 and 3, and consists in placing upon the bar B a metallic rest-plate, E, which is provided with a bracket, e, through which the bar B passes, this bracket serving to prevent the plate from shifting or turning upon the bar B. The ends of the sleepers D of two respective sections of the bridge are fastened to the plate by the pins b''. The boards D' are arranged transversely upon the sleepers D, and may be immovably secured in any suitable manner. If the bridge be employed by a retreating army, a number of men may take up the rear sections of the bridge as fast as the troops pass over, and thus successful pursuit may be prevented. If from any cause the bridge should take fire, it is manifest

that the fire could be confined to very small
limits by disconnecting the sections.

Having thus described my invention, what I
claim as new therein, and desire to secure by
Letters Patent, is—

The arrangement of the trestles A A, sills
C, or check-blocks C', the transverse connect-
ing and supporting bar B, and the longitudi-
nal sleepers D, the whole being adapted for

joint use, substantially in the manner and for
the purpose set forth.

The above specification of my improved
swamp-bridge signed this 6th day of Septem-
ber, 1864.

JOHN J. ALISCS.
